Primary Examiner — Garth Rademaker*Assistant Examiner* — Samantha Q Lawrence(74) *Attorney, Agent, or Firm* — McAndrews Held & Malloy, Ltd.(57) **CLAIM**

The ornamental design for a nasal dilator, as shown and described.

DESCRIPTION

FIG. 1 is a front view of a first embodiment of a nasal dilator showing my new design;

FIG. 2 is a top plan view thereof;

FIG. 3 is a right side elevation view thereof;

FIG. 4 is a front view of a second embodiment of a nasal dilator showing my new design;

FIG. 5 is a top plan view thereof; and,

FIG. 6 is a right side elevation view thereof.

The broken lines shown in FIGS. 2-3 and FIGS. 5-6 illustrate portions of the nasal dilator device that form no part of the claimed design. The oblique shade lines in the drawings represent a transparent or translucent surface, and not surface ornamentation.
